UNITED STATES PATENT OFFICE.

ABRAHAM LEVINE, OF BROOKLYN, AND LOUIS OFFERMAN, OF NEW YORK, N. Y.,
ASSIGNORS TO PRESTO METAL STAMPING CORPORATION, OF NEW YORK, N. Y.,
A CORPORATION OF NEW YORK.

ATTACHING MEANS FOR SEPARABLE-FASTENER ELEMENTS.

1,397,382.

Specification of Letters Patent.

Patented Nov. 15, 1921.

Application filed June 7, 1921. Serial No. 475,580.

To all whom it may concern:

Be it known that we, ABRAHAM LEVINE and LOUIS OFFERMAN, citizens of Russia, and residents, respectively, of the city of 5 New York, borough of Brooklyn, in the county of Kings and State of New York, and of the city of New York, borough of Bronx, in the county of Bronx and State of New York, have invented a new and Improved 10 Attaching Means for Separable-Fastener Elements, of which the following is a full, clear, and exact description.

This invention relates to improvements in means for attaching separable fastener elements to flexible supports, particularly to a novel means for attaching a hasp to the flap of a brief case, pocket book, music roll, or similar container.

It is customary to rivet these hasp members to the flap of a brief case or the like, and the primary object of this invention is to provide a hasp, which carries its own attaching means, which may be quickly and easily attached, and which will be a time 25 and labor saving device.

A further object is to provide a hasp member of this character, which will be simple and practical in construction, durable and efficient in use, neat and attractive 30 in appearance, and comparatively inexpensive to manufacture.

With these and other objects in view, the invention consists in certain novel features of construction and combinations and arrangements of parts, as will be more fully hereinafter described and pointed out in the claim.

In the accompanying drawings:—

Figure 1 is a perspective view of an un- 40 attached hasp member embodying our invention; and

Fig. 2 is a view in longitudinal section through the flap of a brief case, illustrating the hasp in applied position.

Referring in detail to the drawings, we have illustrated one element of a separable fastener, which comprises a sheet of mate-

rial 5, bent along longitudinal lines until it is substantially V-shaped in cross section. A hasp 6, engageable with the other separable fastener element (not shown) is rigidly attached to one outer face of the plate. 50

One free edge of the plate 5 carries a plurality of integral prongs or spurs 7, and the other free edge of the plate is beveled 55 or rounded, as indicated at 8.

In attaching the plate to a support, such as the flap of a brief case or similar article, the edge of the flap designated by the reference numeral 9, is inserted between the 60 opposite sides of the plate 5. The free edges of the plate are then forced toward each other by a suitable tool, the spurs 7 piercing the fabric of the flap 9, and when they come in contact with the beveled cam surface 8 65 being upset, as indicated in Fig. 2, so that they firmly grasp the fabric.

It is to be understood that we do not claim as novel the particular shape of the hasp member shown, but claim rather the 70 specific means for attaching any conventional form of hasp member to a flexible support.

Various slight changes and alterations 75 might be made in the general form and arrangement of the parts described without departing from the invention and hence we do not wish to limit ourselves to the precise details set forth, but shall consider ourselves at liberty to make such slight changes 80 and alterations as fairly fall within the spirit and scope of the appended claim.

We claim:

A separable fastener element including a plate, bent along longitudinal lines into substantially V-shape, spurs carried by one edge of the plate, said plate being bent longitudinally adjacent its other edge to provide a cam surface, said surface being engageable with the spurs to upset the same when the 90 edges of the plate are advanced toward one another.

ABRAHAM LEVINE.
LOUIS OFFERMAN.
